and having a central log or wooden cylinder and a number of wooden logs which are interlocked with the central log or cylinder to form a log cabin or house. The logs are formed with a number of annular grooves which are formed in the ends of the logs so that they may be interlocked with each other.

The present invention relates to an improvement in the construction of a log cabin or house, the logs being formed with a number of annular grooves which are formed in the ends of the logs so that they may be interlocked with each other.

UNITED STATES PATENT OFFICE

DAVID E. GREENE, OF BOONE, NORTH CAROLINA

BUILDING TOY

Application filed March 18, 1928. Serial No. 348,013.

The present invention relates to improvements in toys and has reference more particularly to a toy comprising a multiplicity of members or parts in the form of logs that are so constructed as to provide material for the building of diminutive log cabins, forts, bridges, kennels, chairs, benches, pens, fences and the like.

One of the important objects of the present invention is to provide a building toy of the above-mentioned character which will prove educational to develop a child's constructive inclination, the toy being further unique and fascinating.

A still further object resides in the provision of a building toy of the above-mentioned character that does not require any unusual skill in assembling the parts together to form a predetermined structure, the log-forming members being constructed at their ends with annular grooves to facilitate interlocking engagement with angularly disposed adjacent logs regardless of the portion of the log or logs that is grasped by the child during the building of the house or cabin or other piece of furniture.

A further object is to provide a building toy of the above-mentioned character wherein the parts may be put up in a neat display box for sale in stores and the like, and which box provides a receptacle for holding the parts when the same are not in use.

Another important object is to provide a building toy of the above-mentioned character which is simple in construction, inexpensive, strong and durable and further well adapted for the purposes for which it is designed.

Other objects and advantages of the invention will become apparent from the following description when taken in connection with the accompanying drawing.

In the accompanying drawings wherein like reference characters indicate corresponding parts throughout the same;

Figure 1 is a perspective view of a log cabin embodying the features of the present invention.

Figure 2 is a top plan view of the cabin without the roof structure.

Figure 3 is a sectional view taken approximately on the line 3-3 of Figure 1.

Figure 4 is a detail perspective view of one of the building parts.

Figure 5 is a similar view of another one of said parts.

Figure 6 is a detail perspective view of one of the gable elements used in constructing a toy log cabin with my improved parts.

Figure 7 is a detail perspective view of one of the planks utilized for forming the roof structure.

Figure 8 is a detail perspective view of one of the cylindrical parts; and

Figure 9 is a similar view of one of the semi-cylindrical logs.

In the drawings wherein for the purpose of illustration is shown the preferred embodiment of my invention, the numeral 1 designates generally a log cabin that has been constructed with the logs and other parts of my invention. The front wall of the log cabin is denoted by the numeral 2, the rear wall by the numeral 3, the side walls by the numeral 4 and a roof by the numeral 5. There is formed in the front wall a central doorway 6 while a window 7 is formed in one of the side walls 4.

In constructing the log cabin, there is employed a series of elongated cylindrical wooden logs such as are shown at 8 in Figure 8 and semi-cylindrical logs 9 of the same length as the cylindrical logs 8 are also employed. Shorter cylindrical logs 10 as well as semi-cylindrical logs 11 of the size as the cylindrical logs 10 are also used in the construction of this log cabin.

The logs 10 and 11 are approximately three-quarters of the length of the logs 8 and 9. Relatively short cylindrical and semi-cylindrical logs 12 and 13 respectively also form a salient part of the present invention.

Each of the logs 8 and 10 are formed adjacent their respective ends with annular grooves 14 while the end portions of the semi-cylindrical logs 9 and 11 are formed with semi-annular grooves 15. Each of the short logs 12 is formed at its central portion with an annular groove 16 whereas each of the shorter semi-cylindrical logs 13 is formed

with a semi-annular groove 17 at its central portion and this construction is clearly shown in the drawings.

Cylindrical logs 18 which are of a length substantially equal to one-half the length of the cylindrical logs 10 are also employed and the ends of the logs 18 are also formed with annular grooves similar to the annular grooves 14, the grooves formed in the end portions of the cylindrical logs 18 being shown at 19.

In constructing a miniature log cabin, certain of the semi-cylindrical logs are placed on the ground or floor or other supporting surface so as to form the bottom of the side walls 4. A cylindrical log 8 is disposed across the rear end portion of the semi-cylindrical logs 9 with the grooves 14 having interfitting engagement with the grooves 15. A pair of semi-cylindrical logs 13 are arranged at the front side of the cabin in spaced relation to form the base of the doorway 6 and then the cylindrical logs 18 are positioned across the forward ends of the semi-cylindrical logs 9 and the semi-cylindrical logs 13 so that the annular grooves 19 formed in the ends of the logs 18 will have interfitting engagement with the grooves 14 formed in the logs 9 and the grooves 17 formed in the semi-cylindrical logs 13 as clearly shown in Figure 1.

Extending across the grooved inner opposed ends of the cylindrical logs 18 are the relatively short cylindrical logs 12, the grooves 16 of the logs 12 having interfitting engagement with the grooves 19 of the logs 18. In a similar manner, the side wall forming logs cooperate with the outer ends of the front wall and rear wall logs. Additional logs 18 are employed in conjunction with the side walls to form the window 7 and cylindrical and semi-cylindrical logs 12 and 13 are also employed in connection with the window forming portion of the side wall.

A cylindrical log 8 extends across the top of the front wall 2 as well as across the top of the rear wall 3 while semi-cylindrical logs extend across the top of the side walls 4 to support the transversely disposed planks 20 and arranged on these planks are the gable pieces 21. Additional planks 22 are disposed in edge to edge relation across the forward and rear edges of the gable elements 21 whereby to provide a gable roof structure for the log cabin 1.

When the parts are arranged as shown in Figure 1, the log cabin will be self-sustaining and the interfitting parts of the logs will prevent accidental collapsing of the structure. While I have shown the building logs as being utilized in the construction of a log cabin, it is to be understood that the logs may be equally as well used in the building of chairs, benches, fences, kennels, bridges, forts and other structures. This building toy

preferably consists of fifty-six pieces that are put up in a box and packed compactly so as not to occupy much space and a child or grown person will find this building toy instructive and fascinating. By constructing the interfitting portions of the logs in the manner as shown and described, it is not necessary to place the logs in any particular manner in assembling the parts for the formation of a particular building structure so that any child can use the building toy without following any complicated instructions or requiring the use of tools to assemble the parts.

A building toy of this character may be manufactured and sold at a very low cost and due to its simplicity, the parts can be readily and easily assembled or disassembled.

While I have shown the preferred embodiment of my invention, it is to be understood that minor changes in the size, shape and arrangement of parts may be resorted to without departing from the spirit of the invention or the scope of the appended claims.

What I claim is:

1. A toy building comprising a plurality of imitation logs formed with annular grooves adjacent their ends adapted to be assembled in superposed relation with each other to form a predetermined structure, intersecting logs between the adjacent ones of the superposed logs, said superposed logs having interfitting engagement with the intersecting logs as and for the purpose described.

2. In a toy building, a plurality of cylindrical imitation logs of different sizes, each being formed with an annular groove adjacent their ends, and semi-cylindrical logs of different sizes having semi-annular grooves formed therein for interfitting engagement with the annular grooves formed in the cylindrical logs when the logs are assembled to form a predetermined structure.

3. In a toy building, a plurality of imitation logs formed with annular grooves adjacent their ends, the annular grooves being formed to receive grooved portions of cooperating logs.

In testimony whereof I affix my signature. DAVID F. GREENE.
